US00D931447S

(12) **United States Design Patent** (10) Patent No.: **US D931,447 S**
(45) Date of Patent: **** Sep. 21, 2021**

(54) **REINFORCEMENT ARMS AND COLLAR FOR A CANNULA TIP**

(71) Applicant: **ANGIODYNAMICS, INC.**, Latham, NY (US)

(72) Inventor: **Kevin Swift**, Brighton, MA (US)

(73) Assignee: **ANGIODYNAMICS, INC.**, Latham, NY (US)

(**) Term: **15 Years**

(21) Appl. No.: **29/773,300**

(22) Filed: **Mar. 9, 2021**

Related U.S. Application Data

(63) Continuation of application No. 29/703,049, filed on Aug. 23, 2019, now Pat. No. Des. 916,281, which is a continuation-in-part of application No. 15/295,529, filed on Oct. 17, 2016, now abandoned.

(57) **CLAIM**

The ornamental design for reinforcement arms and collar for a cannula tip, as shown and described.

DESCRIPTION

FIG. 1 is a perspective view of reinforcement arms and collar for a cannula tip comprising the new design;

FIG. 2 is a side view thereof;

FIG. 3 is a top view thereof; and,

FIG. 4 is a bottom view thereof.

The broken line showing is included for the purpose of illustrating portions of the article and forms no part of the claimed design.

1 Claim, 4 Drawing Sheets
